terms illustrated by the accompanying drawing, it is to be understood that numerous changes or modifications in the shape, size and materials may be resorted to without departing from the spirit and scope of the invention as claimed hereinafter.

I claim:

In a spraying device, a nozzle mounted intermediate of its ends for universal swinging movement, a driven rotary shaft, a socket plate secured to the shaft and rotatable therewith, the plane of the socket plate being at a right angle to the axis of the shaft, said nozzle having an outer discharge end and an opposite inner end provided with a ball, and a socket in said socket plate in which the ball is swivelly disposed, said socket being spaced radially from the axis of the shaft and being revolved by the shaft in a predetermined circle around the axis of the shaft for revolving each of the ends of the nozzle in a circle of a predetermined diameter.

GEORGE R. CHAPIN.
